SHAPED CHARGE GUN FOR WELL CASINGS OR THE LIKE

Maurice P. Lebourg, Houston, Tex., assignor to Schlumberger Well Surveying Corporation, Houston, Tex., a corporation of Texas

Filed May 1, 1961, Ser. No. 64,970

Term of patent 14 years

(Cl. D30—1)

Fig. 1

Fig. 2

Fig. 3

FIG. 1 is a view in perspective of a shaped charge gun for well casings or the like showing my new design;
FIG. 2 is a view in front elevation; and

FIG. 3 is a view in top plan, the bottom plan being the same as the top plan.

I claim:

The ornamental design for a shaped charge gun for well casings or the like, as shown and described.
